COMBINATION SINGLE, DOUBLE, AND TWIN COUCH BEDS

Joseph Martin, Brooklyn, N. Y., assignor to
United States Cabinet Bed Co., Brooklyn, N. Y.,
a corporation of New York

Application April 29, 1933, Serial No. 668,570

10 Claims. (Cl. 5—18)

This invention relates to beds in general and more especially to combination single, double and twin couch beds.

Among the objects of the present invention, it is aimed to provide an improved combination single and double couch bed having a main bed frame, an extension bed frame, and independent mattress or upholstered portions in which the main bed frame is frictionally anchored against movement and has a bed spring spaced from the floor to form a chamber, the extension bed frame is mounted on rollers, has a bed spring and is adapted to be moved under the bed spring of said main bed frame in single bed formation and is adapted to be moved outwardly, adjoining said main bed frame in double bed formation and in which there is provided a side board along the longitudinal free edge of said extension bed frame between which and the back of the main bed frame there are disposed alongside of one another mattress or upholstered portions in double bed formation.

It is still another object of the present invention to provide a combination single and double couch bed in which two independent mattress or upholstered portions are disposed alongside of one another between the back of the main frame and the front board of the extension bed frame temporarily to anchor the two bed frames in double bed formation.

It is still another object of the present invention to provide an improved combination single and double couch bed having a main bed frame, an intermediate carriage connected to said main bed frame by collapsible bars, and an extensible bed frame connected to said carriage, the outward movement of the carriage and extensible bed frame being determined by said bars in extended position where said extensible bed frame is disposed adjacent to said main frame, and mattress or upholstered members being disposed between the back of said main frame and the end board of said extensible bed frame to anchor said extensible bed frame against accidental movement under said main frame.

It is still another object of the present invention to provide an improved equalizer or guide for guiding the extensible bed frame into and out of extended position relative to a main bed frame.

It is still another object of the present invention to provide an improved temporary connection between the extensible bed frame and a supporting carriage operatively connected to a main bed frame by means of which connection the ex-

tensible bed frame can with facility be liberated to form an independent twin bed movable to any remote distance from said main bed frame.

It is still another object of the present invention to provide an improved combination single, double and twin couch bed which can be manufactured at low cost, which has a small number of operating parts and which can be operated with facility by the average housewife unskilled in mechanical movements.

These and other features, capabilities and advantages of the invention will appear from the subjoined detail description of specific embodiments thereof illustrated in the accompanying drawings in which

Figure 1 is an end view of a couch bed made according to one embodiment of the present invention in single bed formation;

Fig. 2 is an end view partly broken away of said embodiment in double bed formation;

Fig. 3 is a fragmental plan view of said embodiment in double bed formation;

Fig. 4 is a fragmental section on the line 4—4 of Fig. 2;

Fig. 5 is an end view of the main bed frame of said embodiment partly in section showing the main bed frame separated from the extensible bed frame in independent twin bed position;

Fig. 6 is an end view of the extensible bed frame of said embodiment partly in section showing the position of the extensible bed frame when separated from the main bed frame in independent twin bed position;

Fig. 7 is a plan view of the several elements of said embodiment in single bed formation separated from the back and arms of the couch forming structure;

Fig. 8 is a fragmental perspective showing the improved connecting means by which the extensible bed frame may be connected to the intermediate supporting carriage of the embodiment illustrated in Fig. 1;

Fig. 9 is a transverse section of another embodiment shown in double bed formation;

Fig. 10 is an enlarged transverse section of said second embodiment in single bed formation; and

Fig. 11 is a side or front elevation of the extension bed section of said second embodiment in raised position.

In the embodiment shown in Figs. 1 to 8, there is illustrated a metal frame constituting the main bed section 1 connected to a couch forming structure having an upholstered back 2, and arm embracing side wall members 3 and 4 which structure is preferably supported on rollerless

feet 5 and 6 to form a substantial frictional engagement with the supporting floor.

The bed section 1 embraces generally a rectangular frame 7 supporting a flat bed spring 8, rear downwardly extending supports 9 which preferably as illustrated do not extend to the supporting floor and a bar 10 extending from one support 9 to the other at a short distance below the level of the bed spring 8. The bar 10 preferably consists of an angle iron having a longitudinally extending flange 11 provided with a recess 12 formed therein to receive the stud 13 connected to the elongated link 14. Pivotally connected to the flange 11 at one corner thereof is another elongated link 15 preferably corresponding in length to link 14. At the other end of the flange 11, there is pivotally connected one end of a short link 16 the other end of which is pivotally connected substantially at the middle 20 of the elongated link 14. The links 14 and 15 are preferably arranged to move while in parallel relation to one another and their forward free ends are connected to the horizontally extending flange 17 of the crosspiece 18 of the intermediate carriage 19 constituting an auxiliary member for supporting the extension bed section when moving such extension bed section into and out of double bed formation.

This flange 17 has an elongated slot 20 corresponding in length to the slot 12 in the flange 11 and has slidably mounted therein a stud 21 formed at the end of the link 15. One end of the flange 17 has pivotally connected thereto the front end of the link 14. The other end of the flange 17 has pivotally connected thereto one end of the short link 22 which has its other end pivotally connected substantially to the middle of the elongated link 15. The short link 22 is adapted to move in parallel relation to the short link 16 so that the links 14, 15, 16 and 22 together with the flanges 11 and 17 will effect a parallel movement throughout. In other words, the flange 17 of the carriage 19 will be maintained in parallel relation to the flange 11 whether in extended position as illustrated in Fig. 3 or in collapsed position as illustrated in Fig. 7 and throughout its movement into and out of extended position.

The bar 18 of the carriage 19 is preferably connected adjacent its ends to the brackets 23 and 24 having journals at their lower ends to receive the larger rollers or casters 25 and 26.

The links 22, 15, 14 and 16 are preferably composed of flat stock extending in a horizontal direction and since the links 22, 15, and 14 are connected to the horizontally extending flange 17 of the carriage 19, the carriage 19 will with facility be maintained in an upright position without any additional supporting means. The carriage 19 will of course be supported by the rollers 25 and 26 to be moved into and out of extended position on the rollers 25 and 26.

The front bar 21 of the rectangular frame 7 consisting of an angle iron preferably has its vertically extending flange 28 extending upwardly from the flange 29, see particularly Figs. 2 and 5 and in such position this flange 28 acts as a limiting stop for the mattress or upholstered member 30 when the main bed section 1 is used as a twin bed independent and separated from the extension bed section.

The frame 7 is preferably mounted at a level above the supporting floor to form a chamber to receive the extension bed section 31 without its mattress or upholstered member 32. The ex-

tension bed section 31 embraces essentially a rectangular frame 33 for supporting a flat spring 34, and has a front board 35 extending vertically along its front bar 36 which board 35 is preferably covered with upholstery 37 as indicated in Fig. 6.

The board 35 extends both above and below the level of the frame 33 to correspond with and complete the design of the lateral extensions 38 of the side wall members 3 and 4 when the extension bed section 31 is moved into single bed formation, that illustrated in Fig. 1.

The extension bed section 31 when separated from the main bed section 1 as an independent twin bed, is movably mounted upon rollers or casters. Adjacent the front board 35 and extending downwardly from the side bars 39 and 40 of the frame 33 there are provided the brackets 41 having journaled at their lower ends the larger casters or rollers 42. Extending downwardly from these two bars 39 and 40 adjacent to the rear end of the frame 33 there are provided the brackets 43 having journaled at their lower ends the small rollers 45. The brackets 43, see particularly Fig. 8, have angle irons 46 provided with rearwardly horizontally extending flanges 47 disposed at a level below the bed spring 34 and provided with orifices 48.

These orifices 48 are adapted to receive the rounded heads 49 extending upwardly from the flange 17 of the carriage member 19. For convenience of construction, these heads 49 are formed on the pivot pins connecting the links 22 and 16 to the flange 17.

In single bed formation, the mattress or upholstered portions 30 and 32 are preferably mounted one above the other as illustrated in Fig. 1 from which it will also appear that the upholstered portion 32 is preferably wider than the upholstered portion 30 and overlaps the front edge of the upholstered portion 30 to register with the front face of the upholstered portion 31 of the board 35 to complete the upholstered design of the couch.

In this single bed formation, the extension bed section 31 connected by the cooperation of the orifices 48 with the studs 49 will of course be disposed under the frame 7 of the main bed section 1 and the carriage 19 will be disposed adjacent to the rear wall of the couch with the links 22, 15, 14 and 16 collapsed or in folded position as indicated in Fig. 7.

When it is desired to convert the couch bed from single bed formation to double bed formation, it will only be necessary to engage the end board 35 and move it outwardly into the position illustrated in Fig. 2 and then remove the mattress or upholstered portion 32 into the space formed between the end board 35 and the mattress or upholstered member 30. When the mattress 32 is so positioned it will as indicated form a block or obstacle to prevent the inward movement of the extension bed section and thus anchor the same against accidental movement under the main bed section.

Preferably the mattress member 32 may have a couch covering on one face thereof to face outwardly when the mattress member 32 is disposed on the mattress member 30 in couch bed formation or disposed so that its couch covering will face downwardly in single bed formation. Similarly when the mattress member 32 is mounted on the extension bed section for double bed formation, the couch covering face 75

will preferably be disposed to face downwardly with the mattress covering facing upwardly.

The links 22, 15, 14 and 16 as aforesaid will serve by cooperation with the slots 12 and 20 not only to limit the outward movement of the extension bed section, that is predetermine its outward position in double bed formation but will also serve to guide the extension bed section in a predetermined parallel movement relative to the sides 3 and 4 and back 2 of the couch.

From the foregoing, it will also appear that when the extension bed section is moved into double bed formation, it will be mounted to ride outwardly on the rollers 25, 26 and 42 with the 15 rollers 45 elevated above the supporting floor as indicated in Fig. 2.

When it is desired to convert this device into two independent twin beds, it is only necessary to remove the extension bed section 31 from its 20 connection with the carriage 19, that is by raising the brackets 47 to clear the studs 49 and then permit the extension bed section to be moved outwardly upon the rollers 45 and 42. Thereafter the mattress member 32 may be positioned 25 on the frame of the extension bed section 31 as heretofore explained when it will form an independent twin bed as shown in Fig. 6 independent of the twin bed formed by the main bed section 1. On the other hand of course the twin 30 bed conversion may also take place after the extension bed section has been moved outwardly with the carriage 19 in which case the extension bed section 31 will be separated from the carriage 19 as heretofore explained by raising the 35 one end of the extension bed section to permit its brackets 47 to clear the studs 49.

When the extension bed section forms a twin bed, it will of course be mounted as illustrated in Fig. 6 on the rollers 45 and 42. After the bed 40 sections have been separated into twin bed formation, and it is then desired to convert it into single bed formation, it will be only necessary to remove the mattress member 32, place it on the mattress member 30, connect the extension 45 bed section to the carriage 19 by lifting the rear end of the same so that the orifices 48 of its brackets 47 will receive the studs 49 and then press the extension bed section inwardly into the chamber formed below the frame 7.

50 As illustrated in Fig. 2, the mattress 32 is also deeper than the mattress 30 so that when this mattress 32 is disposed on the extension bed section 31 in double bed formation, the upper faces of the mattresses 30 and 32 will be in alignment with one another.

55 Preferably to prevent the accidental displacement of the extension bed section when disposed in single bed formation, a suitable latch is provided, such for instance as the upwardly turned flange 36 secured to the front bar 36 of the extension bed section 31 having an outer cam face to strike the nose of the latch bar 27 pivotally connected to the vertically extending flange of the front bar 27 of the frame 7 and having its 60 nose extend down through an opening formed in the horizontal flange of said front bar 27 and into the path of movement of the upper cam face of the flange 36 when the extension bed section is moved inwardly.

70 In order to release the extension bed frame from the latch bar 27, it will only be necessary to pass the hand between the mattress and the front board 37 to raise the latch bar 27 and thereupon exercise an outward pressure on the 75 extension bed section 31.

In the embodiment illustrated in Fig. 9, the main bed section 50 is substantially identical to the main bed section 1 of Fig. 1 except that it is made according to the studio bed type and thus is not provided with a back and arms such as the back 2 and arms 3 and 4 of the main bed section 1.

The extension bed section 51 on the other hand instead of having a fixed upper level as is the case with the extension bed section 31 of the embodiment illustrated in Fig. 1, has a vertically movable upper frame member 52. Otherwise the extension bed sections 51 and 31 are substantially identical.

In this second embodiment there are provided 15 two frames, to wit the upper frame 52 and lower frame 53. The lower frame 53 is substantially rectangular having two end angle irons 54 and two longitudinally extending or side angle irons 55 and 56, the angle iron 56 being disposed at 20 the front face of the extension bed section 51 and has secured to the vertically extending flange the facing board 57 which extends the full length of the front face of the extension bed section 51 and also extends from a level below the lower 25 face of the angle iron 56 to a level, see Figs. 9 and 10, where it will just clear the lower face of the upper front facing board 58 of the main bed section 50.

The lower frame 53 is mounted on rollers having secured to and extending down from the horizontally extending flanges of the end bars 54 adjacent to the angle iron 56 the brackets 59 to which the large rollers 60 are journaled. To the outer face of the vertically extending flange of 35 the angle iron 55, there are secured two angle irons 61 and 62, each having a horizontally extending flange 63 in which there is provided an orifice similar to the orifice 43 of the bracket 46 illustrated in Fig. 8, and each angle iron also 40 having a vertically extending flange 64 to the outer face of which there is provided a bracket 65 to which there is journaled the smaller roller 66.

The upper frame 52 is similarly substantially 45 rectangular having the end angle iron 67 and the longitudinally extending side angle irons 68 and 69. Corresponding ends of the upper and lower frames 52 and 53 are connected to one another by the sets of cross bars 70 and 71. The 50 upper end of a cross bar 70 in the present instance is pivotally connected to the vertically extending flange of a side bar 67 and the lower end of such cross bar is provided with a pin 72 slidably mounted in the slot 73 formed in the 55 vertically extending flange of a side bar 54. The cross bar 71 on the other hand has its lower end pivotally connected to the vertically extending flange of a side bar 54 and its upper end provided with a pin 74 slidably mounted in the 60 slot 75 formed in the vertically extending flange of the side bar 67. The cross bars 70 and 71 of each set are pivotally connected to one another to form a cross in expanded position, that shown 65 in Fig. 9.

The pin 76 for pivotally connecting the bars 70 and 71 to one another is preferably pivotally connected to the lifting bar 77 which is provided with a pin 78 at its lower end slidably mounted in the slot 79 formed in the vertically extending flange 70 of a side bar 54. To cooperate with the cross bars 70 and 71 to form a stabilizer, there is in the present instance provided a lever 80 and link 81, the lever 80 being pivotally connected at its lower end to the vertically extending flange of the bar 75

56 and provided with a pin 82 at its upper end to slide in the slot 83 formed in the vertically extending flange of the angle iron 69. The link 81 on the other hand is pivotally connected at its lower end to the middle of the lever 80 and at its upper end is pivotally connected to the vertically extending flange of the angle iron 69.

For connecting the extension bed section 51 to the main bed section 50, there is provided an intermediate carriage 19' constituting an auxiliary member for supporting the extension bed section 50 while moving into and out of double bed formation, substantially identical to the carriage 19 of the embodiment illustrated in Fig. 1, which carriage 19' is similarly provided with a stud 49'. This carriage 19' is also connected to the main bed section 50 by linkage similar to the linkage 15, 22, and 14, 16 of the embodiment illustrated in Fig. 1 only one set being shown in the present 20 instance, to wit the set 14', 16'.

I claim:

1. The combination with a main bed section having a longitudinally extending vertical side wall, of a longitudinally extending strip of angle iron having a vertically extending web secured to the inner vertical face of said side wall and a horizontally extending web extending forwardly, an extension bed section, an auxiliary supporting member adapted to be connected to said extension bed section and movable with said extension bed section into single bed formation alongside of said main bed section, said supporting member having roller supporting brackets and a longitudinally extending strip of angle iron with its 35 vertically extending web secured to said brackets and its horizontally extending web extending rearwardly toward said side wall, and parallel linkage composed of flat stock with their extended faces disposed substantially parallel and 40 horizontal and connected face to face with the horizontally extending webs of the angle irons of said supporting member and of said side wall to facilitate the parallel movement of said extension bed section and supporting member into 45 and out of double bed formation, said parallel linkage consisting of two pairs of parallel links, each having a long link and a short link, the short link of each pair having one of its ends pivotally connected face to face to the long link 50 of a pair intermediate its ends, the end of the long link of one pair being pivotally connected face to face to the horizontally extending web of the angle iron of said side wall, the other end of said long link being slot and pin connected face 55 to face to the horizontally extending web of the angle iron of said supporting member and the other end of said short link being pivotally connected face to face to the horizontally extending web of the angle iron of said supporting member, 60 and one end of the long link of the other pair being pivotally connected face to face to the horizontally extending web of the angle iron of said supporting member, the other end of said latter long link being slot and pin connected face to 65 face to the horizontally extending web of the angle iron of said side wall, and the other end of the short link of said latter pair being pivotally connected face to face to the horizontally extending web of the angle iron of said side wall.
- 70 2. The combination with a main bed section having a bed spring forming frame disposed at a level above the supporting floor to form a chamber, of an extension bed section supportable independent of said main bed section having a bed spring forming frame disposed at a level below

the bed spring frame of said main bed section, an auxiliary supporting member adapted to be removably connected to said extension bed section and movable with said extension bed section into said chamber, means for extensibly connecting 5 said supporting member to said main bed section, and means for connecting the extension bed section to said supporting member consisting of upwardly extending studs formed on said supporting member and orifices formed in the extension bed section large enough freely to receive said studs whereby said extension bed section may be readily disconnected from said supporting member by merely raising one side of said extension bed section to clear said studs.

3. The combination with a main bed section having a bed spring disposed at a level above the supporting floor to form a chamber, of an extension bed section supportable independent of said main bed section having a bed spring disposed at a level below the bed spring of said main bed section, an auxiliary supporting member, collapsible links connecting said supporting member to said main bed section, and upwardly extending studs on said supporting member, there 25 being orifices formed in one side of said extension bed section large enough freely to receive said studs and thus removably connect said extension bed section to said supporting member whereby said extension bed section may be readily disconnected from said supporting member to be used as an independent bed by merely raising one side of said extension bed section to clear said studs.

4. The combination with a main bed section having a bed spring disposed at a level above the supporting floor to form a chamber, of an extension bed section supportable independent of said main bed section having a bed spring disposed at a level below the bed spring of said main bed section, an auxiliary supporting member, means for movably connecting said supporting member to said main bed section, and upwardly extending studs on said supporting member, there being orifices formed in one side of said extension bed 40 section large enough freely to receive said studs and thus removably connect said extension bed section to said supporting member whereby said extension bed section may be readily disconnected from said supporting member to be used as an 45 independent bed by merely raising one side of said extension bed section to clear said studs.

5. The combination with a main bed section having a bed spring forming frame disposed at a level above the supporting floor to form a chamber; of an extension bed section supportable independent of said main bed section having a bed spring forming frame, a lower frame, linkage for connecting the bed spring frame of said extension bed section to said lower frame to be 55 moved vertically relative to said lower frame; an auxiliary supporting member adapted to be connected to said lower frame and movable with said extension bed section into said chamber; means for extensibly connecting said supporting member to said main bed section, and means for connecting the extension bed section to said supporting member consisting of upwardly extending studs formed on said supporting member and orifices formed in said lower frame large enough 60 freely to receive said studs whereby said extension bed section may be readily disconnected from said supporting member to be used as an independent bed by merely raising one side of said extension bed section to clear said studs.

6. The combination with a main bed section having a bed spring disposed at a level above the supporting floor to form a chamber; of an extension bed section supportable independent of said main bed section having a bed spring, a lower frame, and linkage for connecting the bed spring of said extension bed section to said lower frame to be lowered when and before being moved into said chamber and to be raised after being removed from said chamber, there being orifices formed in said lower frame; an auxiliary supporting member; means for movably connecting said supporting member to said main bed section; and upwardly extending studs on said supporting member, the orifices formed in said lower frame being large enough freely to receive said studs and thus removably connecting said extension bed section to said supporting member whereby said extension bed section may be readily disconnected from said supporting member to be used as an independent bed by merely raising one side of said extension bed section to clear said studs.

7. The combination with a main bed section having a longitudinally extending vertical side wall and a bed spring forming frame disposed at a level above the supporting floor to form a chamber to one side of said side wall and below said frame, of a longitudinally extending strip of angle iron with its vertically extending web secured to the inner vertical face of said side wall and with its horizontally extending web extending forwardly, an independently supportable extension bed section having a bed spring forming frame disposed at a level below the bed spring frame of said main section, an auxiliary supporting member connectable to one side of said extension bed section and movable with said extension bed section into said chamber, said supporting member having roller supporting brackets and a longitudinally extending strip of angle iron with its vertically extending web secured to said brackets and its horizontally extending web extending rearwardly toward said side wall, and parallel linkage composed of flat stock with their extended faces disposed substantially parallel and horizontal and connected face to face with the horizontally extending webs of the angle irons of said supporting member and said side wall to facilitate the parallel movement of said extension bed section into and out of double bed formation, said parallel linkage consisting of two pairs of parallel links, each having a long link and a short link, the short link of each pair having one of its ends pivotally connected face to face to the long link of a pair intermediate its ends, the end of the long link of one pair being pivotally connected face to face to the horizontally extending web of the angle iron of said side wall, the other end of said long link being slot and pin connected face to face to the horizontally extending web of the angle iron of said supporting member and the other end of said short link being pivotally con-

nected face to face to the horizontally extending web of the angle iron of said supporting member, and one end of the long link of the other pair being pivotally connected face to face to the horizontally extending web of the angle iron of said supporting member, the other end of said latter long link being slot and pin connected face to face to the horizontally extending web of the angle iron of said side wall and the other end of said short link of said latter pair being pivotally connected face to face to the horizontally extending web of the angle iron of said side wall.

8. The combination with a main bed section, of an extension bed section supportable independent of said main bed section, an auxiliary supporting member adapted to be removably connected to said extension bed section and movable with said extension bed section relative to said main bed section, means for extensibly connecting said supporting member to said main bed section, and means for connecting the extension bed section to said supporting member consisting of upwardly extending studs formed on said supporting member and orifices formed in the extension bed section large enough freely to receive said studs whereby said extension bed section may be readily disconnected from said supporting member by merely raising one side of said extension bed section to clear said studs.

9. The combination with a main bed section having a bed spring disposed at a level above the supporting floor to form a chamber, of an extension bed section supportable independent of said main bed section having a bed spring disposed at a level below the bed spring of said main bed section, an auxiliary supporting member, means for movably connecting said supporting member to said main bed section, upwardly extending studs on said supporting member, and a longitudinal side bar below the level of the spring member of said extension bed section, there being orifices formed in said longitudinal side bar of said extension bed section large enough freely to receive said studs and thus removably connect said extension bed section to said supporting member.

10. The combination with a main bed section, of an extension bed frame supportable independent of said main bed section, an auxiliary supporting frame adapted to be removably connected to said extension bed frame and movable with said extension bed frame relative to said main bed section, means for extensibly connecting said supporting frame to said main bed section, and means for connecting the extension bed frame to said supporting frame consisting in studs formed on one of said frames and orifices formed in the other of said frames large enough freely to receive said studs whereby said extension bed frame may be readily disconnected from said supporting frame by merely raising one side of said extension bed frame to clear said studs.

JOSEPH MARTIN.
